UNITED STATES PATENT OFFICE.

JOHN G. HENDERSON, OF KEOKUK, IOWA.

WASHING-MACHINE.

SPECIFICATION forming part of Letters Patent No. 402,927, dated May 7, 1889.

Application filed December 10, 1888. Serial No. 293,152. (No model.)

To all whom it may concern:

Be it known that I, JOHN G. HENDERSON, of Keokuk, in the county of Lee and State of Iowa, a citizen of the United States, have invented a new and useful Improvement in 5 Washing-Machines, which is made and used substantially as set forth hereinafter, and as shown in the accompanying drawing, in which the figure is an elevation of the apparatus, a 10 part of the tub being broken away to show inner parts.

The object of this invention is to form a simple, cheap, and practical washing-machine, which can be easily operated without complex 15 machinery, and which can be easily and quickly transformed into either a tub or machine. The invention consists in several parts and features of arrangement, substantially as set forth.

20 The tub B is of simple ordinary construction. It is provided with ribs D on its bottom suitably arranged for rubbing clothing to be washed. It has a central tube, C, projecting up through its bottom, with a flange and 25 bolts below for attachment and packing to prevent leakage; and it has handles E of ordinary form on opposite sides and a handle, F, projecting from one side adapted for turning the tub by.

30 The frame A has a head centrally on top, with legs G projecting for its support, and suitably braced. It has a central shaft, H, projecting up from its top or head to enter the tube C of the tub B. The upper end of 35 this shaft is square to hold a slide, I; above the tube C and keep it from turning with the tub. The lower end of shaft H is round, and it and the top of the head of frame A are arranged to form bearings for the end of tube 40 C and the tub to turn on.

The rubber head K has suitable rubbing- 45 ribs on its under side and arms L arched up holding the slide I above on shaft H and adapted to be used as handles by the opera-

The tub B may be used as an ordinary wash-tub in the preparatory and finishing stages of washing, either mounted on the support A or separate from it, and a cork or other means of preventing the water running out by the 50 tube C may be used when needed.

When the clothing has been prepared for rubbing, the tub is mounted on its support, as shown, with the clothing and a suitable quantity of suds therein, and the rubber head K 55 is put in on top with its slide I on shaft H. The tub is then turned back and forth or round and round by handle F, while the head K is held fixed on the top of the clothing with suitable pressure by handles L until 60 the clothing has been suitably rubbed. During this operation the head K is held from turning by the square shaft H in its slide I, and it is allowed to rise and fall by the slide moving on the shaft. The head K may be 65 lifted from time to time for turning and adjusting the clothing for the proper treatment.

Various modifications may be made.

I claim—

1. The tub B, provided with a projecting 70 handle, F, a series of ribs on its bottom, and a central tube, C, in combination with a support, A, having a shaft, H, squared along its upper part to prevent a slide turning thereon, and a rubber head, K, provided with ribs below and with handles L and a slide, I, above 75 mounted on shaft H, so as to slide without turning.

2. The tub B, provided with a central vertical tube, C, and having handle F, in combination with a support and shaft, H, to fit in 80 said tube, and with a floating rubber, K, held by said shaft and adapted to hold it while the tub is rotated to wash clothing under said rubber, substantially as set forth.

JOHN G. HENDERSON.
